UNITED STATES PATENT OFFICE

HARRY BUDD, OF PRYOR, OKLAHOMA

WASHING APPARATUS

Application filed August 13, 1928. Serial No. 299,431.

My invention relates to laundry apparatus and more particularly to a device of that character for washing articles of clothing or the like, the principal object of the invention being to provide a device for easily and thoroughly cleansing articles of clothing or the like without injury to their fabric.

In accomplishing this and other objects of the invention I have provided improved ¹⁰ tails of structure, the preferred forms of which are illustrated in the accompanying drawings, wherein:

Fig. 1 is a perspective view of the apparatus embodying my invention mounted in ¹⁵ functional position in a tub.

Fig. 2 is a sectional view of the apparatus illustrating mounting of the agitating rollers in their respective supports.

Fig. 3 is a cross section on the line 3—3, ²⁰ Fig. 2, illustrating the yielding and pivotal mounting of the lower roller supporting plates and the position assumed by the plates when the upper agitating roller is rotated in the direction indicated.

Fig. 4 is a similar view illustrating the ²⁵ reverse position assumed by the supporting plates when the agitating roller is oppositely rotated as indicated.

Fig. 5 is a perspective view illustrating in ³⁰ detail parts of the washer in disassembled but related order.

Fig. 6 is a detail perspective view of a tensioning device for the upper agitating roller.

Fig. 7 is a transverse section on the line ³⁵ 7—7, Fig. 5.

Referring more in detail to the drawings:

1 designates a rectangular-shaped tub preferably constructed of sheet metal comprising side walls 2 and end walls 3 having vertical ⁴⁰ upper portions and converging from substantially half their height toward a bottom 4 provided with a drain plug 5.

Mounted between the vertical portions of the side walls and substantially mid-way between the ends of the tub is a washer 6 having frame members 7 and 8 secured to the side walls of the tub by bolts 9.

The frame members, preferably of wood, are rectangular in shape, each member being provided with a downwardly extending

transverse slot 10 terminating in the lower half of a bearing 11 for a purpose later to be described, the slot dividing the upper half of the frame into paired heads 12. Each frame member is further provided with an ⁵⁵ inwardly facing recess 13 extending from the bottom of the frame to a transverse line slightly below the bearing 11. On each side of this recess and near its upper end is a deeper and relatively narrow recess 14, communicating with a bore 15 extending throughout the length of the head 12.

Each head is provided with a reinforcing cap 16 having depending flanges 17 whereby it is secured to the head with screws 18.

An aperture 19 in the cap 16 aligns with the bore 15 and is adapted to receive the shank of an eye bolt 20, adjustably retained in position by a wing nut 21. Positioned in each bore 15 is an expansion spring 22 ⁷⁰ provided with a hook at its upper end for engaging the eye of the bolt 20, the lower end of the spring extending to the slot 14 to engage a movable bearing member 23 comprising a cross arm 24 having a centrally depending bearing arm 25. The ends of the cross arm are bent outwardly and laterally and are provided with notches 26 for receiving the lower hooks on the springs 22.

It will be apparent that when the movable ⁷⁵ bearing member is positioned in the frame member, the expansion springs exert an equal amount of tension on each end of the cross arm.

However, by influence of alternate pressure on either side of the depending arm ⁸⁰ 25, the bearing member 23 may be oscillated, the range of travel being limited by the walls of the recess 13.

Fixed to the lower end of the depending arm 23 and extending laterally and inwardly ⁸⁵ therefrom is a pivot pin 27 adapted to pivotally mount a supporting plate 28 comprising an oblong end wall 29 having a depression 30 in its upper edge and an outwardly directed depending peripheral flange 31. Integral with the inner face of the end wall and formed in an arcuate line is a series of bearing bosses 32 for a purpose presently to be described. The center bearing boss extends ⁹⁰ downwardly forming an integral part of the ⁹⁵ 100

peripheral flange, and a bearing aperture 33 near the lower edge of the flange is adapted to journal the pivot pin 27.

In the foregoing description only one of the frame members and its associated parts, including a supporting plate, have been described in detail since one set of parts is a duplicate of the other.

10 Rotatably mounted between oppositely directed supporting plates 28 and in the arcuate series of bearing bosses thereof, are a series of lower agitating rollers 34 having bearing pins 35 adapted to rotate in the bearings 32.

15 On the ends of the supporting plates and extending inwardly from the flanges 31 are ears 36, provided with apertures 37. Tie bars 38 secured to the ears 36 by bolts 39 serve to hold the oppositely directed supporting plates with the series of lower agitating rollers rotatably mounted therebetween in a single unit. An upper corrugated agitating roller 40, also preferably of wood, is mounted above this unit by shaft portions 41 and 20 42 journaled rotatably in the bearings 11 heretofore described.

25 Tensioning means for yieldingly urging the upper roller in frictional contact with the lower set of rollers comprises upper bearing halves 43 for engaging the shaft portions 41 and 42, the bearings being provided with bosses 44 for receiving the lower ends of compression springs 45, positioned in the slots 10. The upper ends of the springs are restrained by latch members 46 having ears 47 for engaging the lower faces of the reinforcing caps 16, wings 48 providing means for manipulation of the latch members.

30 The shaft portion 41 is provided with a head 49 for limited endwise movement, and the shaft portion 42 terminates in a crank 50 provided with a handle 51 for operating the washer.

35 Assuming the apparatus to be constructed and assembled as described, its operation is as follows:

40 Referring to Fig. 3 the crank 49 and corrugated roller 40 which constitutes the driving and agitator element of the apparatus are shown in clockwise movement and under this condition, the roller 40 frictionally engaging the lower rollers 34 causes tilting movement of the mounting plates on their pivot pins 27 against the tension of the springs 22 which 45 support the bearing members 23 and the lower roller unit. The center roller 34 mounted on the center bearing boss serves as a lever to tip the end plates anti-clockwise on the fulcrum pins 27. The tilting movement of the plates being in an opposite direction to that of the roller 40 causes a greater contact pressure between the engaging rollers at one side of the mounting plates, whereas reverse movement of the agitator element causes reverse tilting of the lower roller unit

and the exertion of pressure on the opposite rollers.

In using the apparatus, an article of clothing or the like, taken from soapy water in the tub, is entered between the engaging rollers 40 and 34 and operation of the crank 49 to and fro induces tilting movement of the lower roller and folding and unfolding of the article as it is shifted from side to side by the roller 40 and the alternate pressure and suction produced by the fluted upper roller in its alternate contact with the lower rollers produces a quick, easy and efficient cleansing effect.

30 What I claim and desire to secure by Letters Patent is:

1. In washing apparatus of the character described, opposed frame members having inwardly facing recesses, an upper roller supported by the frame members above the recesses, a lower roller unit comprising supporting plates each having an arcuate series of roller-receiving openings, and rollers mounted in said openings, and means extending in said recesses for pivotally supporting said plates from the frame members.

2. In washing apparatus of the character described, opposed frame members having inwardly facing recesses, an upper roller supported by the frame members above the recesses, a lower roller unit comprising supporting plates each having an arcuate series of roller-receiving bearing bosses, and rollers mounted in said bosses, and means extending in said recesses and resiliently supported by the frame members for pivotally supporting said plates.

3. In washing apparatus of the character described including opposed frame members having bearings to receive a corrugated roller, and a corrugated roller mounted on said bearings, a roller unit comprising plates each having a bearing aperture adjacent its lower edge and an arcuate series of bearing bosses above said aperture, and rollers mounted in said bosses, and unit-supporting means each including an arm dependingly supported by a frame member and having an inwardly projecting pivot pin for mounting in said bearing aperture of the plate.

4. Washing apparatus including opposed frame members, an upper roller rotatably mounted on said frame members, a lower roller unit including end plates and a series of rollers rotatably supported by the end plates, bearing members for rockingly supporting the lower roller unit, and resilient means supporting the bearing members from the frame members for frictional contact of the upper roller with the rollers of the lower unit.

5. Washing apparatus including opposed frame members having inwardly facing recesses forming stop walls, an upper roller rotatably mounted on said frame members, a lower roller unit including end plates and

a series of rollers rotatably supported by the end plates, bearing members for rockingly supporting the lower roller unit, resilient means supporting the bearing members from the frame members including arms extending in said recesses and adapted to engage said walls for limiting rocking movement of the lower roller unit.

6. Washing apparatus including opposed frame members, bearing members resiliently supported by the frame members, said bearing members including cross arms having depending arms provided with pivot pins, a lower roller unit including a plurality of rollers, said unit being rockably mounted on said pivot pins, an upper roller rotatably supported by the frame members, means urging the upper roller towards the lower rollers, and means including one of said lower rollers operable by the upper roller upon rotation of the upper roller to tilt the lower roller unit oppositely to the rotative movement of the upper roller.

7. Washing apparatus including opposed frame members, bearing members resiliently supported by the frame members and adapted to rock, said bearing members including cross arms having depending arms provided with pivot pins, a lower roller unit including a plurality of rollers, said unit being rockably mounted on said pivot pins, an upper roller rotatably supported by the frame members, means urging the upper roller into frictional contact with one of said lower rollers, means including said lower roller operable by the upper roller upon rotation of the upper roller to tilt the lower roller unit oppositely to the rotative movement of the upper roller, and means including recessed portions of the frame members for limiting rocking movement of the bearing members.

8. In washing apparatus of the character described, including supporting means, and an operating roller rotatably mounted on the supporting means, a roller unit comprising a series of agitating rollers, end plates rockably mounted on the supporting means having bearings for rotatably supporting the agitating rollers adjacent the operating roller including a central bearing normally located in the vertical plane of the axis of the operating roller, and means tending to urge the operating roller into frictional contact with the one of said agitating rollers which is supported by said central bearing, said operating roller being adapted to press material being fed to the apparatus against said last named agitating roller to rock the unit for swinging others of said agitating rollers toward the operating roller.

In testimony whereof I affix my signature.
HARRY BUDD.
